SUGAR CANE CUTTING KNIFE

Herman J. B. Scharnberg, Fort Wadsworth, N. Y.

Application June 10, 1931, Serial No. 543,326

24 Claims. (Cl. 146—121)

This invention relates to improvements in sugar cane milling apparatus, and more especially to improvements in the cane cutting knives, and the method of holding the knives in their 5 holders and for supporting the holders.

Cane knives are extensively used for the shredding of the long stalks of cane, before they enter the crushing rolls, but during the operation many of the knife blades break off, close to the 10 holder, and through bolt or rivet holes in the shank of the blade, which are used for fastening the blades to the holder by means of bolts or rivets.

Breakage of the blades at these points is due 15 to the fact that the curved shaped blades now in use render these blades very much out of balance, and when the blades revolve at very high speed, centrifugal stresses are set up, causing the metal to become fatigued. The broken 20 blade moves with the cut cane to the crushing rolls, damaging rolls and decreasing the efficiency of the crushing plant. Many blades break directly in the holder, due to striking on iron or other hard material coming in with the cane, 25 and which can not be cut by the knives while rotating at very high speed.

The bolts and rivets which hold the knife blades to the holder are under a heavy shearing stress while the set is in operation; and if they 30 become loose, as they often do during operation, the vibration set up at the point of blade fastening causes the bolts or rivets to break, and the complete knife is thrown into the cane before 35 the failure is discovered. Due to the location of the rivets and bolts in the holder, their projecting heads are dragged through the cut cane, causing an extra power consumption.

When one of the blades breaks off, the whole 40 rotating knife set is thrown out of balance, causing the shaft on which the knife holder is mounted to become bent due to heavy vibration, especially since it is common practice to use one 45 long continuous key in the shaft for holding 18 to 21 knife holders each having two knife blades bolted or riveted thereto. The amount of vibration and shaft stresses set up in the rotating element depends entirely on how much of the 50 blade is broken off, the smaller the piece, the safer it is to keep the equipment in service until a new blade can be installed. In order to install a new blade, the bolts or rivets holding the shank of the blade to the holder have to be removed, and as there are sometimes as many 55 as 5 bolts, or rivets, considerable time is lost,

in making this change, as the crushing plant has to be shut down during this time.

When the cutting edges of the blades become dull or worn the entire knife blades have to be removed for sharpening, which requires that 5 from 144 to 168 bolts or rivets have to be removed, in order to unfasten the blades from the holder. This requires much time, and in a cane crushing plant it is of great importance that a minimum of time be lost in making repairs 10 during the grinding season, because the available time is limited by weather condition.

Other objects of the invention are to improve generally the simplicity and efficiency of such apparatus and to provide a device or apparatus 15 of this kind which is economical, durable and reliable in operation, and economical to manufacture.

Still other objects of the invention will appear as the description proceeds; and while here 20 in details of the invention are described and claimed, the invention is not limited to these, since many and various changes may be made without departing from the scope of the invention as claimed in the broader claims.

The inventive features for the accomplishment of these and other objects are shown herein in connection with an improved cane knife construction which, briefly stated, includes a series of blade holders on a shaft each holder 30 comprising arms, and a hub having a wedge face.

A side face of each arm has a tapering recess having undercut side walls, each recess receiving an outwardly tapered blade-shank having side edges fitting under said under-cut walls, the inner end of the shank having a wedge face engaged by a wedge nut held in wedging engagement between the wedge faces of the hub and blade, by a bolt passing through said arm and the wedge nut.

In the accompanying drawings, showing, by way of example, two blades and a blade holder, embodying my invention.

Fig. 1 is a fragmental side elevation showing the shaft carrying holders and showing the blades in edge elevation;

Fig. 2 is a fragmental elevation showing the end of the shafts and the side faces of the 50 blades and holders;

Fig. 3 is a fragmental side elevation showing a holder and blade;

Fig. 4 is a fragmental sectional view taken on the line 4—4 of Fig. 3;

Fig. 5 shows a section on the line 5—5 of Fig. 3;

Figs. 6 and 7 are respectively side and edge elevations showing another form of blade.

5 Fig. 8 is a sectional view, similar to Fig. 5, but showing the shank 44 of the cutter blade in Fig. 6 with a double angle on its edges, when inserted in the seat of the holder.

My invention is shown embodied in a sugar-cane-milling knife set comprising a knife shaft 10 driven by a motor 11 directly coupled to one end of the shaft, a flywheel 12 being carried on the other end, the shaft rotating in bearings 13, 14 adjacent to the motor and said flywheel 15 respectively.

Said shaft 10 has a portion 15 of enlarged diameter adjacent to the bearing 13 to form a stop, and a taper 16, adjacent to, and tapering away from said stop. Jam nuts 18, 19 are 20 respectively received on reversed threads 20, 21 near the other end; and two spiral series of short longitudinal key seats 23, 24, 25, 26 extend between said taper and threads.

A plurality of contacting one-piece blade holders 27, 28, 29, are carried on said shaft and clamped between said stop 15 and a collar 30 against the nut 20. Each blade holder comprises a pair of wide transversely disposed radial arms 27, 28, and a short hub 29, the hubs having flat 30 end faces 32 (Fig. 4) engaging the adjacent hub 29, collar 30 or stop 15, and a central opening 34 received on said shaft and having a longitudinal key seat 33 (Fig. 4), the two end hubs having tapered openings fitting on the shaft 35 taper with a forced fit.

Blades 35 are mounted on said arms as will be explained.

As stated, said shaft has a pair of helically arranged series of longitudinally disposed key 40 seats 23, 24, disposed 25, 26 spirally in opposite directions toward the middle part of the shaft. Short keys 36 in said seats 23 to 26 and 33 (Fig. 4) key said holders to the shaft with the axes of the blades arranged in two helical 45 series of opposite direction, adjacent arms 27 or 28 being here shown advanced 18 degrees apart, as indicated in Fig. 3, and the number of blades being such that the blades of each series are evenly spaced, thereby to distribute 50 the load evenly throughout the cycle of the shaft, said series having helical directions tending to bring the material to the middle part of the shaft to prevent clogging at the ends of the shaft. Obviously a different number and angle 55 for the blades may be used if desired.

Said hubs and stop 15 are provided at their adjacent faces 32 with radial bores 37 (Fig. 3) each having its axis substantially in the plane of said faces, the bore terminating short 60 of the large opening of the hub and receiving a pin 38 (Fig. 1) fitted tightly in each bore, the material adjacent to the bore being peened over the end of the pin to hold the pin in place, whereby said hubs are locked together and 65 transmit twisting strains to said stop 15.

Diagonally opposite side faces of each pair of arms 27, 28 are each provided in its wide face with a wide shallow outwardly tapering recess 40 (Fig. 4) having undercut straight side 70 walls 41 (Fig. 5), a wide flat floor 42, and a transverse outwardly beveled end wall 43 (Fig. 3) forming a continuation of the taper of the hub. Each blade 35 is wide, relatively thin, substantially radially disposed with its center of 75 gravity substantially in its radial axis, and made

preferably principally of mild steel, and comprises an outwardly tapered imperforate flat shank 44 seated in said recess, and a widened active portion 45 having therein a plurality of openings 46 forming one or more divergent legs 5 47, 48, 49, and hardened steel welded to the active edge 50, 51 on the active portion form cutting edges.

The cutting edge 50, 51 is forwardly intermediate curved, as at 50, and gradually extending back, as at 51, to approximately coincide for a considerable distance with the path of revolution of the extreme outer part of the edge.

The side edges 53 of each shank outwardly 15 converge and are beveled to fit under said undercut edges 41 of the recess, whereby, in operation, centrifugal force on the blade wedges the shank 20 between the undercut edges 41 and flat against the floor 42 of the recess.

The inner end edge 55 of the shank is disposed substantially perpendicular to the axis of the shank and terminates short of the inner end 43 of the recess to form a wedge-receiving space 56, the edge portion 55 being beveled toward the 25 floor of the recess, to form a wedge face 57. A lug 58 (Fig. 7) is integral with or welded on the exposed face of the shank to form a continuation of said wedge face 57 at the radial axis of the shank. A wedge nut 60 (Figs. 3 and 4) in the 30 middle part of said space 56 wedges between wedge faces 61 (Fig. 4) and 57 of the hub and blade. The holder arm is provided with a radially slightly elongated bolt opening 62, registering with the wedge-nut opening, loosely receiving the bolt 63 having a large diameter threaded portion 64 received by the threads of the wedge nut for clamping said wedge nut into wedging engagement with said wedge faces for 35 forcing the shank tightly between the under-cut edges of the recess, to prevent vibration.

The end of said bolt 63 has a reduced diameter portion 65 having threads reverse to, and of less pitch than, the threads of the larger portion and receiving a lock or jam nut 66 engaging the 45 wedge nut.

The end of the spaces 56 are vacant, and the floor thereof is provided with large openings 68 in approximate alignment with bolts 63 of adjacent arms and positioned to facilitate the 50 removal of the nuts and bolts from said adjacent arms.

As stated, the shaft 10 is provided with a separate key 36 for each blade holder, the keyway being cut in such manner, that when the holders 55 are mounted on the shaft, the holders will be preferably about 18 degrees apart, and will form a helical series up to or from the center of the shaft, so that during operation the load on the shaft is constant, because the knives will cut 60 cane throughout the entire cycle.

Because of the independent keys 36 for the holders, it is possible to fit the holders much better to the shaft; and after the holders have all been mounted, they are drawn tight together 65 by means of the large right hand nut 18, which by means of the left handed nut 19 is locked, to prevent the holders from becoming loose on the shaft.

After everything has been drawn up tightly, 70 the hole 37 is drilled between the first holder and the shoulder on the stop, and between every pair of holders; and the round pin 38 is fitted tightly into each hole, set slightly below the surface of the metal, and the edge of the metal 75

is peened over, so that the centrifugal force cannot throw the pins out during operation.

This method of fastening locks the holders together like a solid unit; and should any of the 5 knives hit a piece of iron coming in with the cane, the strain will be transmitted through the holders to the stop 15 on the heavy end of the shaft, diminishing the chances of breaking or bending the shaft at the point where the knife 10 strikes a solid piece of material.

The mounting of the individual knife blades to the holder without bolts or rivets, makes it possible to mount the holders in the form of a helical series on the shaft, which makes it possible 15 to cut the cane or other material very much finer, and the finer the cane stalks are cut up, the higher will be the sucrose recovered from the cane.

Each holder is so constructed, that it can hold 20 two knives, mounted opposite to each other, making each holder unit perfectly balanced. Because of the tapering recess 40, any outward movement of the blade radial to the shaft will force the blade tighter into the recess especially 25 during operation, when centrifugal force will hold the blade tightly in the holder. This makes it impossible for any vibration to be set up between the knife blade and the holder and no breaking of a knife blade at this point will take 30 place. The shank of the blade is not drilled, and therefore no breakage of the blade can take place through bolt or rivet holes.

The bolt 63 for holding the wedged nut is provided with a right hand thread, ten threads 35 per inch, and a left hand thread of nine threads per inch. This is done to prevent the bolt from becoming unscrewed from the wedged nut. The wedged nut having a right hand thread, is locked tight by the lock nut 66, which has left 40 hand threads of greater pitch; and when there is a tendency for the bolt to unscrew from the wedged nut, it will be drawn up tighter, on the left hand thread lock nut. It will not be possible 45 to remove the bolt from the wedge nut without first removing the left hand threaded lock nut.

The bolt hole 62 in the knife holder is radially elongated, and if there is any wear in the tapered fits of holder or shank blade, causing the blade 50 to move radially outwardly, the wedged nut and the bolt can follow outwardly, by action of the centrifugal force, while the equipment is still in service rotating at high speed. Tightening up on the bolt 63 while the equipment is out of service, will also cause the wedge nut to compensate such wear.

The blade shanks 44 of both types of blades, as shown in Figs. 3 and 6 may have their edges 55 tapered on both sides, best indicated in Fig. 8 where the double tapered edges are shown. This form of edge permits of reversing the blades 60 in the bracket tapers 41, when desired without any appreciable loss of strength.

The knife blade is shaped so that during operation it is practically balanced, the center 65 of gravity being almost exactly in the center line of the blade, radially to the center of the shaft. This condition prolongs the life of the blade.

In order to reduce the centrifugal stresses set 70 up in the shank end of the blades, part of the material has been cut out of the blade as at 46, in order to reduce the weight and for other purposes herein stated. Usually heretofore the material used for cane knives is of steel, so that it can be tempered at the cutting edge 75 where all the wear takes place due to cutting

of the cane, the shank end of the blade remaining soft. Due to the width of the material where the temper is drawn, very often cracks develop in the material, on account of uneven cooling; and to prevent this, I cut some of the 5 material out of the blade thus forming a number of legs in the blade, which makes it possible to temper the blade, without cracking it, the legs 47, 48, 49 in the blade being free to adjust themselves to any expansion, or contraction 10 while the cutting edge is being tempered.

This construction also makes it safely possible, to use a very mild steel for cane knives, and to use only for the actual cutting edge a hard steel which is welded to the legs in the 15 blade, without danger of setting up shrinkage stresses at the points where the hard steel is joined to the soft steel. This construction greatly reduces the cost of the blades, as only the cutting edge will have to be renewed after it 20 has worn out.

Should the blade strike on a piece of iron or other hard substance during the regular operation, a fracture would take place in the weakest section of the knife, which is in the outer 25 ends of the legs; and should the cutting edge break at this point, only a very small piece of the knife would be thrown into the cane, and the balanced condition of the rotating set would not be much disturbed, neither would there be 30 much damage done to the crushing rolls, when the small piece of blade passes through with the cane.

Due to the setting and fastening the blade 35 holders on the shaft, my new construction makes it very easy to get to the broken blade to renew it quickly with another blade.

The holder of the knife blades is provided with large holes cast in the metal, on both sides of the bolt hole, so that when it becomes necessary 40 to remove a bolt completely from the holder, the bolt can be removed by passing it through a hole in the adjacent holder. This makes it possible to mount the holders in a helical series on the shaft. 45

The location of the bolts in the holder is such, that at no time do the heads drag through the cane; only the smooth shaped end of the holder does this. This reduces the power consumption 50 greatly and the knife set operates much more smoothly.

In order to get more service out of the cutting edge of the cane knife blade, the curve of the cutting edge is such that the angle between the cutting edge 51 of the blade and 55 the circle the cutting edge describes in a revolution is very small and very long.

The blade 35' (Fig. 6) can also be constructed with a double cutting edge 50', 50'' so that one side can be cutting while the other is dragging 60 backwardly through the cut cane. After one side has become dull, the direction of rotation or the direction of the blade can be reversed, thereby using the other cutting edge. From

actual experience it has been found that a dull cutting edge dragging through the cut cane becomes sharp again due to the abrasive action of the cane, so it will only be necessary to reverse the direction of the rotation of the knives, in 70 order to always cut with a sharp set of knives. While the shank 44 of the blade 35' is not shown reversible in the socket, the changing of a blade 35' from one socket 40 to the other socket 75 40 of the same holder has the effect of revers-

ing the direction of the blade without reversing the direction of rotation of the shaft.

I claim as my invention:

1. In combination, a holder having a recess having undercut outwardly converging side walls and an inner end wall having a wedge face; a blade having a shank, the side edges of said shank fitting under said under-cut walls of the recess, the inner end edge of the shank being formed with a wedge face; a wedge nut wedging between said wedge faces; the holder being provided with a bolt opening registering with the wedge nut opening; the bolt in said opening having a threaded inner portion received by the wedge nut for clamping said wedge nut into wedging engagement with said wedge faces, said bolt having a reverse threaded outer portion; and a jam nut on said outer portion engaging the wedge nut.
2. In combination, a shaft; a series of blade holders on said shaft having arms, the arms being near each other and arranged in a helical series; a blade carried by each arm; means holding the blade on the arm comprising a nut, and a bolt longitudinal to the shaft; each arm having a vacant opening substantially aligned with the bolt of the adjacent arm to facilitate insertion or removal of said bolt.
3. In sugar cane milling apparatus, in combination, a cane knife set comprising a knife shaft; a motor directly connected to one end of the shaft and a pulley carried on the other; bearings for said shaft adjacent to the motor and said pulley; said shaft having a portion of enlarged diameter adjacent to the bearing at the motor end, to form a stop, sets of relatively reversed threads near the other end and longitudinal key seats extending between said taper and threads; jam nuts on said threads respectively; a collar on the shaft against the inner nut; a plurality of contacting blade holders carried on said shaft and clamped between said stop and collar and keyed to said key seats; blades on said holders; said hubs and stop being provided at their adjacent faces with radial bores; and a pin secured tightly in each bore.
4. In a cane cutting apparatus in combination with a shaft, a hub rigidly carried by said shaft and having at opposite sides thereof wedge faces, opposed arms extending from said hub at said faces and having outwardly tapering recesses therein, a blade for each arm, said blades having expanded inner ends disposed in the respective recesses, wedge faces on said ends opposite the first mentioned faces, bolts having wedge nuts disposed between said opposite faces, and bolt stems turnably engaging said nuts for drawing the latter inwardly whereby to urge said expanded ends into said recesses.
5. In a cane cutting device comprising a hub having an arm extending therefrom, said arm having therein an outwardly tapered recess and said hub having an inclined face at the inner end of said recess, said arm having also therein and at the base of said face an elongate aperture, a blade disposed in axial relation with said arm and having an inner expanded end which is disposed in said recess, another inclined face on the last mentioned end and disposed opposite the first mentioned face, a bolt including an axially movable wedge nut and having faces slidably engaging said opposed faces, and a threaded shank turnably mounted in said nut and slidably movable in said aperture, whereby on turning said shank said nut may be drawn inwardly to urge

said expanded end into locking engagement in said recess.

6. In a cutting device in combination with a hub having an arm extending therefrom, said arm having therein an outwardly tapered recess and said hub having an inclined face at the inner end of said recess, said arm having also therein and at the base of said face an elongate aperture, a blade disposed in axial relation with said arm and having an inner expanded end which is disposed in said recess, another inclined face on the last mentioned end and disposed opposite the first mentioned face, a bolt including an axially movable wedge nut and having faces slidably engaging said opposed faces, a threaded shank turnably mounted in said nut and slidably movable in said aperture, whereby on turning said shank said nut may be drawn inwardly to urge said expanded end into said recess, said shank having thereon a reduced threaded terminal, and a lock nut for said terminal.

7. In a cane cutting apparatus comprising a shaft having a hub rigid therewith and including an arm which extends from said hub, a metal blade having its inner end mounted on the outer end of said arm and including adjacent the latter a reduced portion, a terminal band of hard metal having a cutting edge thereon, and spaced legs extending outwardly from said portion and integrally carrying said band.

8. A cane cutting apparatus including in combination a shaft, mutually engaging flat hubs mounted on said shaft, opposed arms extending from each of said hubs, means holding said hubs individually on the shaft so that said arms point in different radial directions, each of said arms having in its inner end and on an arc having its center on the axis of said shaft openings, blades having their inner ends engaged on the outer ends of said arms, and means carried by the first mentioned ends and holding the inner ends of said blades in the engaged position, said means including fastening elements which are disposed between the openings of the respective arms, so that parts of said elements may be disposed in the opening of adjoining arms.

9. In a cane cutting apparatus, the combination of a revolvable hub having opposed arms extending therefrom, each of said arms having at its outer end a relatively long tapered recess the lateral boundary faces of which are undercut, each of said arms having also therein a screw receiving aperture; a blade carried by each arm and including an inner end having a short expanded portion which is provided with lateral beveled edges, so that said portions may be freely placed in the inner ends of the respective recesses and then moved outwardly, whereby to engage said edges against said faces; and means for holding said edges in the engaged position, said means including a screw in each aperture.

10. In a cane cutting apparatus, the combination of a revolvable shaft, a hub rigid with said shaft and having opposed arms expanding therefrom, each of said arms having at its outer end a relatively long outwardly tapered recess the lateral boundary faces of which are undercut, each of said arms having also therein a screw receiving aperture; a blade carried by each arm and including an inner end having a short outwardly tapering portion which is provided with lateral beveled edges, so that said portions may be freely placed in the inner ends of the respective recesses and then moved outwardly, whereby

- to engage said edges against said faces; and means for holding said edges in the engaged position, said means having a screw disposed in each aperture, said screws being adapted to engage the inner ends of said blades.
11. In a cane cutting apparatus, the combination of a revolvable shaft, a hub rigid with said shaft and having opposed arms extending therefrom, each of said arms having at its outer end a relatively long tapered recess the lateral boundary faces of which are undercut, each of said arms having also therein a screw receiving aperture; a blade carried by each arm, each blade including an outer end, an inner end having a short tapering portion which is provided with lateral beveled edges, so that said portions may be freely placed in the inner ends of the respective recesses and then moved outwardly, whereby to engage said edges against said faces; said outer end including a forwardly curved edge carrying portion, the outer terminal part of which is curved rearwardly; and means for holding said edges in the engaged position, said means including a screw in each aperture, said screws being adapted to cooperate with the inner ends of said blades.
12. In a high speed cane cutting apparatus, a high speed shaft; blade holders mounted on the shaft and each comprising an arm spaced from adjacent arms and having a wide outwardly tapering recess having undercut side walls; and a radial blade in each holder comprising a shank having beveled side edges fitting under said undercut walls.
13. In a cane cutting apparatus, a shaft; a series of blade holders secured on said shaft each having a thin radial arm spaced from adjacent arms and each having a wide side face having therein a wide recess having its axis substantially radial to the shaft and outwardly tapering and having side walls each undercut to form a groove adjacent to the floor of the recess, the grooves outwardly converging toward each other; a blade comprising an outwardly tapered shank having its side edges fitting in said grooves; the outer end of the shank beyond the recess being narrow and the inner end of the recess being unobstructed, whereby the shank may be removed by inward and lateral movement.
14. In a cane cutting apparatus, a shaft; a series of blade holders secured on said shaft each comprising a hub on the shaft and a thin radial arm, each arm being spaced from adjacent arms and having a wide side face perpendicular to the shaft; a side face on each arm having a wide recess axially radial to the shaft and outwardly tapering and having undercut side walls giving to the recess a dove-tail shaped cross-section perpendicular to the axis of the recess; a blade comprising an outwardly tapered shank having beveled side edges fitting under said under-cut walls; the taper and bevel of the recess and shank being such that the shank, when wedged in place by centrifugal force is held against outward or lateral movement relative to the recess, and is wedged by the undercut walls against the floor of the recess.
15. In a cane cutting apparatus, a shaft; a series of blade holders each comprising a hub on the shaft, and a thin radial arm each having a wide side face substantially perpendicular to the shaft; said side having a wide recess having its axis radial to the shaft and having outwardly converging undercut side walls giving to the recess a dove-tail shaped cross-section perpendicular to the axis of the recess; a blade comprising an outwardly tapered shank having beveled side edges fitting under said under-cut walls; the inner end of the shank being spaced a distance from the inner end of the recess, and the part of the shank and blade outwardly of the recess being narrower than the recess; said distance and the taper and bevel of the recess and shank, and the width of the narrower part being such that inward movement of the shank toward the shaft unwedges the shank and allows lateral movement of the shank from the recess and such that the shank, when wedged is held against outward or lateral movement relative to the recess, the arms of adjacent holders being sufficiently spaced to admit lateral movement of the shank from the recesses when the holders are secured in place.
16. In combination, a shaft; a series of blade holders on said shaft having arms, the arms arranged in a helical series and disposed closely adjacent to form a deep narrow recess between the arms; blades having shanks carried by the arms respectively; and means holding the blade on the arm comprising a nut and a headed bolt at the inner end of the shank; said nut and the bolt head being disposed in the deepest part of the adjacent recesses and protected by the arms against dragging through the cane.
17. In a high speed cane cutting apparatus, a high-speed shaft; blade holders mounted on the shaft; and a radial blade of mild steel in each holder comprising a shank firmly mounted on said holder; the cutting edge of the blade being intermediately curved and gradually extending back along the path of the extreme outer part of said edge; said blade comprising an active portion having a plurality of one or more approximately radial openings forming one or more divergent legs, and a hardened steel leg portion welded to the side of said active portion to form a cutting edge; said hardened leg being welded at its ends only to form said opening, thereby reducing tendency to crack at the weld; said openings reducing the width of the blade surface, thereby avoiding unequal cooling and cracking when the temper is drawn.
18. In a high speed cane cutting machine, a high-speed shaft; blade holders mounted on the shaft; and a radial blade in each holder comprising a shank firmly mounted on said holder; said blade having one or more approximately radial openings forming one or more divergent legs, said blade having its largest cross section at the inner end of the shank and gradually decreasing in cross-section to near the outer end of the blade, thereby rendering the blade increasingly unlikely to break at points approaching said inner end, thereby reducing the length, cross section and weight of the broken pieces, thereby reducing eccentricity of weight and reducing damage to subsequent parts of the machine.
19. In a cane cutting apparatus, a shaft; blade holders mounted on the shaft; and a radial blade in each holder comprising a shank mounted in the holder; the cutting edge of the blade being intermediately forwardly curved and gradually curved back along the path of the extreme outer part of said edge; said blade being principally of mild steel and comprising a

widened active portion having a plurality of approximately radial inwardly tapered openings forming one or more divergent legs, one of said legs being hardened steel portion welded to the forward part of said active portion formed with a cutting edge, thereby to avoid formation of stresses, during shrinkage, at the points of the welding of the hard steel on the mild steel.

20. In a high speed cane cutting apparatus, a high speed shaft; blade holders mounted on the shaft; and a radial blade in each holder comprising a shank mounted in the holder; the cutting edge of the blade being intermediately curved and gradually extending back to substantially coincide for a considerable distance with the path of the extreme outer part of the edge; said blade being shaped to dispose with its center of gravity substantially in the radial axis of the shank thereby to prevent twisting of the blade and fatigue-causing stresses at said shank and consequent breaking off of the blade at the shank.

21. In a high speed cane cutting apparatus, a high speed shaft; radial blades mounted on the shaft; each comprising a shank; the cutting edge of the blade being forwardly intermediately curved and gradually extending back to substantially coincide for about 18° with the path of the extreme outer part of the edge; said blade being shaped to dispose its center of gravity substantially in the radial axis of the blade thereby to prevent twisting of the blade and fatigue-causing stresses at the inner end of the blade and consequent breaking off of the blade at the inner end.

22. In a high speed cane cutting apparatus, a high speed shaft; blade holders mounted on the shaft and each comprising an arm having a wide outwardly tapering radial recess having undercut side walls; and a radial blade in each holder comprising a shank having beveled side edges

fitting under said undercut walls; the cutting edge of the blade being intermediately curved and gradually extending back to substantially coincide for a considerable distance with the path of the extreme outer part of the edge; said blade being shaped to dispose its center of gravity substantially in the radial axis of the shank thereby to prevent twisting of the blade and fatigue-causing stresses at said shank and consequent breaking off of the blade at the outer end of the tapering recess.

23. In a cane milling apparatus, a shaft having a stop near each end; a series of blade holders having hubs contacting each other on said shaft, end hubs of the series engaging said stops respectively; said hubs and a stop being provided at their adjacent faces with radial bores forming recesses in said faces respectively; parts of the wall of the recesses being inclined to the hub faces; and a pin secured tightly in each bore, said pins tending to push the hubs apart should there be slight relative motion therebetween, thereby tightening the hubs between the stops, thereby to distribute the strain longitudinally and tangentially of the shaft.

24. In a cane milling apparatus, a shaft having a stop near one end, and threads near the other end; a nut on said threads; a series of blade holders having hubs contacting on said shaft, and hubs of the series engaging said nut and stop respectively; said hubs and stop being provided at their adjacent faces with radial bores forming semi-cylindrical recesses in said faces respectively; and a pin secured tightly in each bore, said pins tending to push the hubs apart, should there be slight relative motion between the hubs, thereby tightening the hubs between the stop and nut, thereby to distribute the strain longitudinally and tangentially of the shaft.

40 HERMAN J. B. SCHARNBERG.
